UNITED STATES PATENT OFFICE.

LANDER S. HARRIS, OF DETROIT, MICHIGAN.

REGULATOR FOR SHUNT-WOUND DYNAMOS OR OTHER ELECTRICAL APPARATUS.

SPECIFICATION forming part of Letters Patent No. 411,551, dated September 24, 1889.

Application filed April 27, 1889. Serial No. 308,881. (No model.)

To all whom it may concern:

Be it known that I, LANDER S. HARRIS, a citizen of the United States, residing in Detroit, county of Wayne and State of Michigan, have invented certain new and useful Improvements in Regulators for Shunt-Wound Dynamos or other Electrical Apparatus, of which the following is a specification.

On the 16th of October, 1888, I took out Letters Patent of the United States No. 391,319 for an improvement in electric motors adapted to work with a series machine.

The invention which is the subject of the present application is a modification of the device covered by the said former patent, by which it is adapted to work with a shunt-machine. The distinction will appear in the following description and claims.

I have shown my invention as applied to an electrical motor; but I do not desire to be limited to that particular use of the regulating device, which may be used in connection with other kinds of electrical apparatus.

In the annexed drawings, making a part of this specification, Figure 1 is a side elevation, partly in section, of an electric motor. Fig. 2 is a front view of the same. Fig. 3 is a plan for representing the arrangement of the wires and switch, by means of which the flow of the electrical current is regulated.

The same letters are employed in all the figures in the indication of identical parts.

A is a line-wire leading into the apparatus and furnished with the ordinary safety-fuse. It terminates in a plate B. From this plate the current flows in two directions, a part of it going from the plate to the wire C through the armature, while the residue of the current passes through the wires K, &c., to and through the field, both currents being finally brought together and flowing off on the main line. The wire C is attached to the plate B and leads to a resistance-coil D, from which, in the case as illustrated, four wires, of which there may be more or less, lead through intermediate parts to the armature and carry more or less of the total current, according as they pass through the whole or a part (more or less) of the resistance. The current conveyed by either one of these wires passes through one of a series of plates F F' F'' F''' from which it is carried by an adjust-

able switch G' to a plate B', whence it is led by the wire H to the armature M, and passing through the brushes M' to the binding-post 55 N', and thence through the wire H' to a binding-post connected with the extension H³ of the main line on the other side.

The switch is formed of a non-conductor bar G², pivoted on the central pivot G⁴, which 60 stands on a wooden bar or plate G³. G G' are two independent metal switch-plates, each attached centrally to the bar G², and made of spring-brass bent into the form substantially as shown in Fig. 1, so as to press at 65 both ends upon the surface upon which they are intended to act and accommodate themselves to any irregularity thereof.

I I', &c., to I⁹ are a series of separate plates of metal attached to the base and insulated 70 from one another. These plates are of different width, increasing regularly in each series from I³ to I⁹, the plates I I' I I', forming the first series, being of the same width as are the wider plates I⁴ I⁵ I⁶, forming the second series, and 75 the wider plates I⁷ I⁸ forming the third series, the plate I⁹ being as wide as either of the series. A large wire K, properly wound, is attached to the plate I. A wire K' of less diameter and similarly protected, is attached to 80 plate I'. A still finer wire K² is attached to plate I², and the finest wire of all K³ is attached to the plate I³. A branch wire K⁴ connects the wire K' to plate I⁴, another wire K⁵ connects K² to plate I⁵, another wire K⁶ connects the wire K³ to I⁶, the wire K⁷ connects plate I⁷ to wire K², and the wire K⁸ connects plate I⁸ to wire K³. The plate I⁹ is also connected by the wire K⁹ to wire K³. The wires K K' K² K³ are carried to the field and 85 wound around the cores L L' L² L³, and thence they pass by the return wires (shown in Fig. 3) to the binding-post at the end of the line-wire H³. The switch being arranged as shown in Fig. 3, it will be observed that 90 the metal switch-plate G extends from the plate B to the segmentally-arranged plates I I' I² I³, and its width at the outer end will therefore be sufficient to touch upon all four of said plates. As a consequence, a part of 95 the current entering through the main line A, and all of it which does not pass out through the wire C and the resistance D to the armature, will flow through the plates I 100

$I' I^2 I^3$ to the graded wires $K K' K^2 K^3$, and thence to the extension of the main line H^3 . In this position of the switch the plate G' is connected with the plate F , to which is connected the wire E , taken off at the end of the resistance D , and therefore through which a minimum of the current intended to pass through the armature will pass because it encounters the full force of the resistance. As the plates I^4, I^5 , and I^6 are broader than the plates I, I', I^2 , and I^3 , it follows, therefore, that the end of the switch which was broad enough to cover the four will when that end of the switch is shifted to the left only cover the plates $I^4 I^5 I^6$, and, as neither of these is connected with the coarse wire K , it follows that that wire which carries the largest part of the current to the field is entirely cut out and the current is limited to flow through the wires $K' K^2 K^3$, with which the plates $I^4 I^5 I^6$ are connected by the branch wires $K^4 K^5 K^6$. The same movement of the switch-bar will have carried the switch-plate G' to the plate F' , which is insulated from the adjoining plates, and the current now passing through C will be taken out from the resistance-coil through the wire C' to plate F' , and thence through the switch to the plate B' , and thence to the armature and the main line, as described. As the wire C' is connected with the resistance-coil before the wire forming such coil reaches its end, there will be less resistance than there was when the current passed through E , so that the proportion of the current passing through the armature will have been increased, while the portion of the current which goes to field through only three of the wires $K' K^2 K^3$ will have been proportionately diminished. If, again, the switch-bar is turned farther to the left, the switch G will bear only upon the plates I^7 and I^8 , which are connected with the wires K^2 and K^3 by the branch wires K^7 and K^8 . As now both the wires K and K' have been cut out of the circuit, the amount of the entire current passing through the field-magnet coils will be proportionately diminished. The same movement of the switch-bar will bring the switch G' in contact with the insulated plate F^2 , which takes the current through the wires C^2 from the middle of the resistance, and therefore with an increased force of current due to the diminution of resistance. If, again, the switch is turned until the plate G bears only on the plate I^9 , which is as wide as the switch itself, all of the wires to field will be cut out except the finest wire K^9 , which is connected by the branch wire K^9 with the plate I^9 . The same movement of the switch-bar will have brought the switch G' into contact with the insulated plate F^3 , which is connected by the wire C^3 with the resistance still nearer to the receiving end of the resistance-coil, and consequently the current through $C^3 F^3 B'$ to the wire H and armature will be at its practical maximum, while the current passing to field through the other switch will

connect only with the finest wire and will only be therefore at its minimum. It will thus be seen that by the described arrangement of the wires and switch with a shunt-machine the current may not only be divided, but it will automatically be so divided that as the current to armature increases by cutting out more and more of the resistance so the current to field will automatically be diminished by cutting out wires leading to field, and vice versa, so that as the switch is shifted it operates automatically to increase the current on one set of wires and diminish it on the other, the aggregate current remaining the same.

What I claim as my invention, and desire to secure by Letters Patent, is—

1. In combination with the main-line wire of a shunt-machine, a series of wires $K K', &c.$, of different sizes leading to the field-magnet, a switch G , to direct a portion of the current through one or more of said wires to the field-magnet, a resistance-coil D , and a series of wires $E C', &c.$, and a switch G' , to direct the residue of the current passing with more or less resistance through any of said wires to the armature, substantially as set forth.

2. In combination with the line-wire A and a series of field-wires of different sizes, a switch-plate G' , and successive series of insulated plates arranged in groups of different numbers but equal aggregate width, whereby the switch is connected with all or part of the field-wires, substantially as set forth.

3. In combination with the line-wire A and switch-plate G , a series of field-wires of different sizes, groups of plates $I I', &c.$, the first group connected directly to the field-wires, the next series of one less plates connected by branch wires with all but one of the field-wires, and so on successively with diminishing numbers, but each group in turn occupying a space equal to the full width of the switch-plate, substantially as set forth.

4. In combination with the field-magnet, armature, and line-wire, switch-plates $G G'$, carried on an adjustable switch-bar, a series of wires leading to the field, and plates $I I', &c.$, arranged in groups connecting one or more of said field-wires with the line-wire, and a series of wires leading from the resistance-coil to a series of plates $F F', &c.$, from which a part of the current leads through the switch-plate G' to the armature, whereby the force of the current to the field will be increased or diminished and that of the current to the armature be inversely diminished or increased, substantially as set forth.

5. In combination with the field-magnet and armature of a shunt-machine, a group of wires leading to field and a corresponding group of wires having variable resistance leading to the armature, and switch mechanism connected to said wires, substantially as set forth, so that when there is a maximum of current through the field-magnets there

shall be automatically provided a minimum current to the armature, and vice versa, the current to one decreasing as the current to the other increases by a single movement of 5 the switch mechanism, substantially as set forth.

In testimony whereof I have hereunto set

my hand in the presence of two subscribing witnesses.

LANDER S. HARRIS.
